UNITED STATES PATENT OFFICE

2,449,442

TRAILER TOILET

Arthur G. Agra, Chicago, Ill.

Application October 4, 1947, Serial No. 777,926

5 Claims. (Cl. 4—77)

1

This invention relates to toilets, and has to do more particularly with toilets for use in automobile house trailers and like structures.

In general, automobile house trailers presently in use are not provided with adequate toilets. One of the objects of the present invention resides in the provision of a toilet that is leakproof, sanitary and free of any objectionable odors.

Another object of the present invention resides in the provision of a toilet wherein the water supply and waste disposal systems thereof are so arranged that the pollution from the toilet of the water supply, that may be drawn from a water source used for drinking purposes, washing, bathing, or the like, is effectively guarded against.

A further object of the invention resides in the provision of an inexpensive, simple and compact toilet that will occupy a minimum of space in an automobile house trailer.

Still other objects and advantages of the invention will in part be obvious and in part will hereinafter appear, and they consist generally in the features of construction, combinations of elements and arrangements of parts, which will be exemplified in the constructions to be described, and of which the scope of application will be indicated in the appended claims.

In the accompanying drawings, in which is shown the preferred illustrative embodiments of the invention:

Figure 1 is a plan view of a toilet embodying the principles of the present invention;

Figure 2 is a side elevational view of the toilet of Figure 1;

Figure 3 is a view partly in elevation and partly in vertical section of the toilet of Figure 1, as viewed substantially along the line 3—3 of said latter figures;

Figure 4 is a fragmentary view, partly in elevation and partly in vertical section, taken substantially along line 4—4 of Figure 1, and

Figure 5 is a fragmentary plan view showing a modified manner of connecting the water supply to the toilet.

Referring now in detail to the drawings, the toilet of the present invention comprises an elongated base structure 10, which seats on the floor 11 of the automobile house trailer, and has a toilet supporting portion 12 and a pump supporting portion 13, the base structure having the relative large bore 14 opening through toilet support 12 and pump support 13.

A bowl 15, formed of a plastic or of any suitable material and which is in general of known construction, is provided with a depending tu-

2

bular neck 16 which seats on an interposed gasket 17 on the toilet support 12, to which it is secured in any known or desired manner. The opening 18 defined by neck 16 preferably is disposed concentric with the opening 14a of bore 14, or substantially so. At its upper portion, bowl 15 is provided with a passage 19 extending thereabout and provided with downwardly directed openings, one of which is shown at 21, as is known. At its rear, bowl 15 is provided with the outwardly extending portion 22 and the integrally depending portion 23, both having communicating internal passages, which communicate with passage 19. A horizontally disposed pipe 24 threads into portion 23 and extends therefrom a sufficient distance to clear the side of bowl 15, where it threads into an elbow 25, which elbow 25 has threaded engagement with a vertically disposed pipe 26, (Figure 3). Pipe 26 extends to immediately adjacent the top of bowl 15, where it has threaded engagement with an elbow 27 formed integrally with one end of an elongated valve chamber 28.

Within chamber 28 a flow restriction 29 is provided, which restriction is normally closed by a check valve 31 having one end pivoted at 32 to a web 33 formed integrally with the inner surface of the chamber. A plug 34 threading into an opening adjacent elbow 28 may be removed to

gain access to valve 31. Flow of water through chamber 28 is governed by a water shut-off valve 35 operable by rotation of handle 36. Such valve may be of any known or desired construction and, as shown, is located between plug 34 and the end

of chamber 28 which receives water supply pipe 37. This latter pipe is suitably secured to the bottom of chamber 28, and extends therefrom vertically downwardly and passes through a suitable opening in the floor 11 of the automobile house trailer. When the trailer is parked in a trailer camp, the water supply pipe 37 may be connected to the camp water supply in a suitable known manner, and when the trailer is on the road the pipe 37 may be connected in a known manner to the usual water storage tank of the trailer.

At the end of chamber 28 adjacent pipe 37, a suction responsive valve 38 is connected to and projects from the top of the chamber. Such valve is connected to a return bend 39, which in turn is connected to a pipe 41 that extends vertically downwardly from the bend and passes through a suitable opening in the trailer floor 11, where the pipe is open to atmosphere. Valve 38 may be of any known construction, or it may be

constructed substantially as shown in Figure 4 of the drawings. In the event the water supply to pipe 37 is cut off and the water is drained from that pipe, a partial vacuum would be produced therein, and in chamber 28 if valve 35 is open. When that occurs, the suction responsive valve 38 opens to admit air drawn from pipe 41, into chamber 28 and thence into pipe 37, thus breaking the vacuum in said chamber and latter pipe. Further, any partial vacuum produced in chamber 28 and pipe 37 causes the check valve 31 to be held more tightly against its seat. Accordingly, this valve 31 and the suction responsive valve 38 cooperate to assure that pollution from bowl 15 of the source of water supply cannot occur. That is, of course, of utmost importance, as is recognized by health authorities.

The opening 14b in pump support 13 is controlled by an upwardly opening and downwardly closing valve member 42. This valve is in the form of a gasket 43 and may be formed of an impregnated material, of leather, or of any other suitable material. The gasket 43 extends throughout substantially the full area of the upper surface of support 13, and is clamped between such support and the out turned flange of a pump cylinder 44, which seats on the gasket 43 and is secured to the support 13 as by bolts 45, or in any other suitable manner. An arcuate slot 46 formed in gasket 43 defines the valve member 42. Metal discs 47 and 48 are secured to the upper and lower faces, respectively, of valve member 42, as by screw means 49, or in any other suitable or preferred manner. The disc 47 is of somewhat larger diameter than the opening 14b which is closed by valve member 42. As will be clear from what has been said, valve 42 opens upwardly and closes downwardly and normally is held in a closed position.

A piston 51 fits snugly in pump cylinder 44 and is vertically reciprocable therein. Piston 51 comprises a pair of cup-shaped members 52—53 disposed with their backs in opposed relationship and confining therebetween a pair of pump washers or leathers 54—55, the washers being of sufficient size to be turned over the peripheral flange of members 52—53 and disposed for sliding movement along the inner surface of the wall of cylinder 44. A piston rod 56 has one end threaded through the hubs 57 of members 52—53 and holds such members and washers 54—55 in assembled relationship. Rod 56 extends vertically upwardly in cylinder 44 and passes through a packing gland 58 threaded into a cylinder cover 59, which cover is secured to the cylinder as by the bolts 61. The end of the rod externally of the cylinder threads into a clevis 62. An operating arm or handle 63 is disposed in unbalanced relationship between the arms of clevis 62 and pivotally supported thereon at 64. The short arm of handle 63 engages between one end of a pair of links 65—66 to which it is pivotally secured at 67. The opposite end of links 65—66 are pivotally secured at 68 to lugs 69 suitably formed on cover 59 of pump cylinder 44. Operation of handle 63 will, of course, reciprocate piston 51 vertically in cylinder 44.

Pump cylinder 44 has an integral casting projecting horizontally outwardly from one side thereof forming a pipe 71 having a bore 72 substantially the diameter of bore 14, the bore 72 communicating with cylinder 44 immediately above valve 42. A flange 73 formed on pipe 71 is secured, as by bolts 74, to a flange 75 formed

on one end of an elbow 76. A gasket 77 is confined between flanges 73—75, and this gasket 77 is provided with a check valve of substantially the identical construction of the valve 42, the valve between flanges 73—75 being adapted to open upwardly into elbow 76 and to close toward flange 73. Upon downward movement of piston 51, valve 42 will close and the valve between flanges 73—75 will open, while upon upward movement of piston 51, valve 42 will open and the valve between flanges 73—75 will close. A pipe 78 is connected at 79 to the other end of elbow 76, and extends therefrom downward through the trailer floor 11 for discharge into a suitable bucket or container beneath the trailer or, if desired, the pipe 76 may be connected by a length of hose to any suitable point of discharge. The bore 14, pipe 71 and pipe 76 provide a continuous discharge conduit, as will be understood.

Preliminary to use of the toilet, a substantial amount of water should be admitted to the bowl 15 by opening the valve 35, as will be understood. After the toilet has been used, the piston 51 is reciprocated by operating handle 63. On the upstroke of piston 51 a partial vacuum created thereby within cylinder 44 is effective for opening valve 42, and at the same time is effective for maintaining the valve between flanges 73—75 closed, so that the contents of bowl 15 are drawn through bore 14 and discharged into cylinder 44. On the downstroke of piston 51, valve 42 is closed, and the valve between flanges 73—75 is opened, so that the contents of cylinder 44 are discharged under pressure through pipe 71 and then through the discharge conduit comprising elbow 76 and pipe 78. During this operation the valve 35 remains open and bowl 15 is thoroughly flushed out with clean water, the succeeding upstroke of piston 51 again opening valve 42, and closing the valve between flanges 73—75, so that the water from bowl 15 is discharged into cylinder 44, from which cylinder it is discharged in the succeeding downstroke of piston 51. In that manner, by repeated operation of the piston 51 an appropriate number of times, and thoroughly flushing the bowl 15, the toilet may be maintained in a thoroughly clean and sanitary condition.

In order to prevent formation of a partial vacuum above piston 51 during its downstroke, a pipe in the form of an elongated elbow 81 is connected at one end by suitable fittings 82 to pump cylinder 44 and communicates with the interior thereof immediately below cylinder cover 59. The vertically disposed opposite end of pipe 81 is connected to a coupling 83, which coupling 83 is connected to an elbow 84. This latter elbow is in turn connected to one end of a pipe 85 of larger diameter located at a higher level than the elbow 76. The opposite end of pipe 85 is suitably connected to the upper part of the bend of elbow 76 for communication therewith. A suction responsive valve 86 secured to pipe 85 controls flow of air through a port 87 in said pipe. Valve 86 is of generally known construction and comprises the valve seat 88 having the port 89 normally closed by a ball 91 urged into engagement with seat 88 by a relatively light spring 92. A coupling 93 connects valve 86 with a vent pipe 94, which pipe is lead generally vertically downwardly from coupling 93 and passes through a suitable opening in floor 11 of the trailer where it is open to atmosphere. It will be realized that vent pipe 94,

as well as vent pipe 41, may be passed through the roof of the trailer, if desired.

During downstroke of piston 51, ball 91 is drawn from its seat 88 and air is admitted from pipe 94 into pipe 85 and thence through pipe 81 into cylinder 44 above piston 51, thereby breaking any partial vacuum occasioned by downward movement of piston 51. The pipe 81, elbow 84 and pipe 85 constitute a conduit between cylinder 44 and elbow 76. During upstroke of piston 51, any appreciable amount of liquid which may have leaked past the piston, and is disposed thereabove, will be forced through the aforesaid conduit into elbow 76, it being noted that valve 86 is closed during such upward movement of piston 51 and that no liquid will, therefore, be forced into vent pipe 94. The contents of cylinder 44 are thus effectively discharged through the conduit defined by pipe 71 and elbow 76, and the conduit defined by pipes 81-84 and elbows 76-84, into pipe 78. If the flowing of materials down pipe 78 tends to produce a siphoning action and thereby producing a partial vacuum in pipe 78 and elbow 76, the valve 86 will open admitting atmospheric air to said pipe and elbow, thus assuring that the valve between flanges 73-75 will not be open on the upstroke of piston 51, which, if such were the case, would destroy the partial vacuum below piston 51 necessary for the opening of valve 42.

As shown in Figure 5, the depending portion 23 of the bowl 15 may, if desired, be omitted and, instead of leading pipe 24 into the side of the bowl, the pipe may be connected through a suitable fitting 95 directly to the top of the bowl to communicate with passage 19.

It will be understood that changes in detail may be resorted to without departing from the field and scope of the invention, and it is intended to include all such variations, as fall within the scope of the appended claims, in this application in which the preferred form only of the invention has been disclosed.

What is claimed is:

1. In a toilet for automobile house trailers, and the like, a base structure, a bowl and a substantially vertical cylinder carried by said base structure in spaced relationship, said base structure having a bore communicating with said bowl and cylinder, a normally closed upwardly opening and downwardly closing valve controlling communication between said bowl and cylinder, a piston operating in said cylinder, the cylinder having two outlet passages opening thereinto one adjacent and one remote from the bottom of the cylinder, a normally closed upwardly opening and downwardly closing valve controlling the lower one of said outlet passages, and an outwardly closing and inwardly opening suction responsive valve associated with the other of said outlet passages effective for admitting air thereto responsive to creation of a partial vacuum in said cylinder above said piston.

2. In a toilet for automobile house trailers, and the like, a base structure, a bowl and a substantially vertical cylinder carried by said base structure in spaced relationship, said base structure having a bore communicating with said bowl and with said cylinder at the lower end thereof, a normally closed upwardly opening and downwardly closing valve controlling communication between said bowl and cylinder, a piston operating in said cylinder for withdrawing and discharging the contents of said bowl, the cylinder having at its lower end an outlet through which

the contents of said cylinder are discharged by operation of said piston, a waste pipe, a conduit connecting said cylinder outlet with said waste pipe, a normally closed valve in said conduit for controlling said cylinder outlet, a second conduit connected between said cylinder adjacent the upper end thereof and said waste pipe, and an outwardly closing and inwardly opening suction responsive valve associated with said conduits for admitting air to said cylinder and waste pipe.

3. In a toilet for automobile house trailers, and the like, a base structure, a bowl and a cylinder carried by said base structure in spaced relationship, said base structure having a bore communicating with said bowl and cylinder, a normally closed upwardly opening and downwardly closing valve controlling communication between said bowl and cylinder, a piston operating in said cylinder for withdrawing and discharging the contents of said bowl, the cylinder having an outlet through which the contents of said bowl are discharged by operation of said piston, a waste pipe, a conduit connecting said cylinder outlet with said waste pipe, a normally closed upwardly opening and downwardly closing valve in said conduit for controlling said cylinder outlet, a second conduit connected to said waste pipe and to said cylinder at a point remote from said cylinder outlet, and an outwardly closing and inwardly opening suction responsive valve associated with said conduits for admitting air to said cylinder and said waste pipe.

4. In a toilet for automobile house trailers and the like, a bowl having an outlet opening at its lower end, a reciprocating discharge pump comprising a substantially vertical cylinder and a piston operating therein, said pump having adjacent the lower end of said cylinder an intake opening for communication with said outlet opening and a discharge opening, an inlet valve for said pump controlling communication between said outlet and intake opening, said valve opening toward said piston and closing toward said bowl, a discharge conduit comprising a member extending from and above said discharge opening, an inwardly closing and outwardly opening pump discharge valve controlling said conduit disposed below the high point thereof effective for providing a water seal above said discharge valve when the latter is closed, and a second conduit connecting said cylinder adjacent its upper end to said discharge conduit adjacent the high point thereof for delivering to said discharge conduit liquid from said cylinder above said piston and admitting air to said cylinder above said piston.

5. In a toilet for automobile house trailers and the like, a bowl having an outlet opening at its lower end, a reciprocating discharge pump comprising a substantially vertical cylinder and a piston operating therein, said pump having adjacent the lower end of said cylinder an intake opening for communication with said outlet opening and a discharge opening, an inlet valve for said pump controlling communication between said outlet and intake openings, said valve opening toward said piston and closing toward said bowl, a discharge conduit comprising a member extending from and above said discharge opening, an inwardly closing and outwardly opening pump discharge valve controlling said conduit and disposed below the high point thereof effective for providing a water seal above said discharge valve when the latter is closed, a second conduit connecting said cylinder adjacent its upper end to said discharge conduit adjacent the high point

thereof for delivering to said discharge conduit liquid from said cylinder above said piston and admitting air to said cylinder above said piston, and in inwardly opening and outwardly closing suction responsive valve effective for admitting air to said second conduit upon occurrence of a partial vacuum therein.
